INVENTOR,

D. O. Page, by his attorney
William Prince, Jr. —

UNITED STATES PATENT OFFICE.

DYONISIUS OLIVER PAGE, OF GAINESVILLE, TEXAS.

DOUBLE-FOOT PLOW-STOCK.

SPECIFICATION forming part of Letters Patent No. 314,050, dated March 17, 1885.

Application filed August 11, 1884. (No model.)

To all whom it may concern:

Be it known that I, DYONISIUS OLIVER PAGE, a citizen of the United States of America, residing at Gainesville, in the county of Cooke 5 and State of Texas, have invented certain new and useful Improvements in Double-Foot Plow-Stocks, of which the following is a specification, reference being had therein to the accompanying drawings.

10 My invention has relation to improvements in plows; and it consists in the novel construction and arrangement of its parts.

In the accompanying drawings, Figure 1 is a perspective view of my plow-stock with the 15 plow-points attached. Fig. 2 is a top view of beam *a*, with its ends broken away, and of cross-beam *b*, showing the position on the beam *a*, and the positions it may be made to assume, as seen by the dotted lines *c d*. Figs. 20 3, 4, and 5 are detail views of the same.

My invention is described as follows: On the upper face of an ordinary plow-beam, *a*, I bolt a cross-beam, *b*, by a bolt and nut, *b'*, the bolt passing perpendicularly through its 25 center and perpendicularly through said beam *a*, and near its center. This cross beam *b* is braced in position by two braces, *c c*, one end of the same being pivoted on the upper face of the left-hand end of said cross-beam *b* by bolt 30 or nut, and the other one to the left-hand face of said plow-beam *a* by a bolt and nut, *c'*, the bolt passing horizontally through holes *c'* in said beam *a*, the other brace, *c*, being secured to the right-hand side in a similar manner. 35 This cross-beam *b* has in each end a slot, *b'*, cut longitudinally and perpendicularly. On the lower face of this cross-beam *b* are bolted two plow-standards, *d d*, by bolts and nuts *d' d'*, the bolt passing through the upper end 40 of the slot on the said standards *d d*, and through the slots *b'* in the cross-beam *b*.

It will be seen that I can move said standards inward near the beam or outward to the ends of cross-beam *b* by moving the bolts 45 and nuts *d' d'* along the said slot *b'*, thus making the standards wider apart or closer together, as I may desire. I can also, by means of braces *c c*, set the right-hand plow forward and the left-hand plow back; as seen in Fig. 50 1, or I may move my braces the right one one hole back and the left one one hole for-

ward, and thus bring the two plow-points on a line, as shown by the dotted lines *c* in Fig. 2, or I may move my right-hand brace two holes back and left-hand brace two holes forward, and have my left plow-point in the front and the right-hand point in the rear, as shown by dotted lines *d* in Fig. 2.

My plow-standards *d d* are made of a solid bar of iron bent double and riveted or welded together at their lower ends, and leaving a slot at both ends—one to secure the same to cross-beam *b*, and the other for the plow-point bolt to pass through. In the lower ends of these plow-standards I have V-shaped notches *e*. 55 I have a clip, *f*, having a T-head, the lower face of which is V-shaped and fits into the V-shaped notches *e*. The front face is straight for the upper end of the plow-point *f'* to rest against. This keeps the plow-point from turning. The shank *f''* of the said clip passes through the slot in the standard, and its bolt-head *f'''* bears against the rear face of the heel of the standard *d*. The V-shaped notches keep the clip *f* from slipping up the standard. 70 The clip keeps the plow-point in place, and the bolt passes through the plow-point, thence through slot in standard *d*, thence through bolt-head *f'''*, and is secured by a nut. 75

Having described my invention, what I claim as new, and desire to secure by Letters Patent, is—

1. In a double-footed plow, the combination of the beam provided with transverse holes *c'*, the cross-bar *b*, having slots *b'*, the pivot-bolt *b'*, and the adjustable braces *c*, independently pivoted to the cross-bar, substantially as shown and described, and for the purposes set forth. 85

2. The slotted standard *d*, having on its front face the notches *e*, and the plow-point, in combination with the clip *f*, having a T-head whose lower face is V-shaped to fit in one of the notches *e* of the standard, substantially as shown and described, and for the purposes set forth. 90

95 In testimony whereof I affix my signature in presence of two witnesses.

DYONISIUS OLIVER PAGE.
